WARP DRIER WITH AIR RECIRCULATING MEANS

Paul R. Rose, East Orange, N. J.

Application February 20, 1945, Serial No. 578,845

5 Claims. (Cl. 34—154)

1

This invention relates to a device for drying lengths of material.

One important application of the device is for the drying of warp after it has been sized, and the invention is described herein in connection with this application.

An object of the invention is to provide a drying method and apparatus which is simple, practical, and efficient.

Another object of the invention is to provide an improved drying apparatus, which may be rapidly cooled when the supply of heated air is cut off.

Another object of the invention is to provide a method and apparatus for achieving more uniform drying of strip material.

Another object of the invention is to provide a drying apparatus which is operative without damage to material retained therein beyond the normal drying interval.

Another object of the invention is to make it possible to increase the speed of travel of a length of textile material during a drying step, as for example the drying of warp and the sizing thereon.

Another object of the invention is to provide means safeguarding against the impairment of material due to oven drying.

Another object of the invention is to make possible the employment of air heated to within the range of from 200° to 600° F., or higher, to accelerate the drying of textile material.

Other objects of the invention will be in part obvious or in part pointed out hereinafter.

The invention accordingly consists in the features of construction, combinations of elements, arrangements of parts, and in the several steps and relation and order of each of said steps to one or more of the others thereof, all as will be pointed out in the following description, and the scope of the application of which will be indicated in the following claims.

The invention will best be understood if the following description is read in connection with the drawings, in which,

Figure 1 is a side elevation of an embodiment of the invention; and

Figure 2 is a plan view taken on the line 1—1 of Figure 1.

The term "air" is used herein in a broad sense, inclusive of any gas, or gases used for heating or cooling in accordance with the invention.

In accordance with the invention a length of the material to be dried is passed into and out of

5 a drying chamber, and, while it is travelling within said chamber, air heated above room temperature, and preferably well above 200° F. is brought into contact with the material to dry it, and means are provided for obtaining a flow of room air into and through said chamber to speedily exhaust the heated air from said chamber and to reduce the temperature therein to protect the material from over drying, as for example, in the event that the travel of the material stops for any reason. Various means such for example as fan means may be employed to exhaust the heated air from the chamber but preferably the treatment chamber comprises an elongated, substantially vertically extending passage from which heated air may be speedily exhausted when the supply of heated air is cut off, due to the difference in weight between the heated air and air at room temperature the speed of exchange of room air for highly heated air being aided if desired by means, such as said fan means. Preferably the length of material is passed through both an upward and a downward flight within said passage whereby its period of contact with the 10 conditioned air within the passage is doubled and drying efficiency is promoted since the material travels first with and then against the flow of air through said passage. As will be more fully explained means are provided for regulating the quantity of heated air brought into contact with the material, and the extent of the area within which heated air is brought into contact with the material.

20 As illustrated herein a length of material such, for example, as a length of warp 10, is shown passing into and out of a treatment chamber 11, embodying our invention, after being sized. The chamber 11 comprises a central vertically extending portion A, and side portions B, and C, which serve as by-passages for the recirculation and reconditioning of air from chamber A as will be more fully described. The central portion A has a bottom opening 12, and an exhaust port 13, at the top, so that an upward flow of room air may be obtained through said chamber when the supply of heated air is cut off. Extending substantially vertically from the bottom opening 12 toward the top exhaust port 13, the air distributing headers 14 and 15 are provided, being preferably of substantial height and of a width on the order of the width of the material to be dried, but of a lesser width than the width of the drying chamber so that heated air brought into contact with the material between the headers may

be circulated laterally around the ends of the headers as will be more fully explained.

It will be seen that the headers 14 and 15 provide between them a narrow channel P, thus carrying further the channel-like character of chamber 11, and at the top of this channel, and preferably adjacent to chamber exhaust port 13, a roller 16 is provided over which extends the material to be dried. As illustrated herein a length of material, in the form of a length of warp, is led upwardly within said channel P, after being sized and passed through the pairs of squeeze rolls 17, and 18, of the sizing bath 19, and, after passing around roller 16, is led downwardly through channel P, in a flight which is preferably parallel to its upward flight, and out of bottom opening 12 and around guide roller 20 in the direction of the arrows. Both the upward and downward flights of the material are preferably divided into a plurality of planes as by splitter rolls 21, which serve to open the length of warp into a plurality of sheets, thereby separating adjacent warp threads and preventing them from sticking together while at the same time providing space between adjacent warp threads so that air can be brought into contact with the threads individually thereby facilitating drying the threads and the sizing thereon.

The headers 14 and 15 which are spaced apart in substantially parallel relation, are preferably slightly inclined to the vertical to facilitate tracking of the warp in the elongated channel formed between the headers.

As illustrated the chamber 11 is divided horizontally by the floor 22, which is cut away to provide space for the headers 14 and 15 but otherwise divides chamber portion A horizontally so that air can pass from below floor 22 to above floor 22 only through passage P. The floor 22 may conveniently be a floor of a mill in which the drying chamber 11 is employed, the chamber extending partly below and partly above said floor, and the latter being cut away to provide for the headers 14 and 15 and for the by-passing of air from passage P and chamber portion A, through chamber portions B and C as will be explained.

Chamber portion A is separated from chamber portions B and C, by the upwardly extending partitions 23 and 24 respectively. Between the top of the partitions 23 and 24 and the top of the chamber the dampers 25 and 26 are provided, which, when closed, serve to complete the partitions 23 and 24 respectively thus entirely separating the air space above floor 22 in chamber portion A from the chamber portions B and C. Chamber portions B and C extend below the level of floor 22 and communicate with the headers 14 and 15. Each of the chamber portions B and C is provided with heater means H, and fan or air impellor means F, whereby when the dampers 25 and 26 are opened air is sucked into chamber portions B and C respectively, past heaters H, by the action of said fan means. The portion of the air thus diverted to chamber portions B, and C, is first heated by the heaters H and then sucked into the fan means and forcibly delivered into the said headers, and discharged therefrom into channel P, preferably through elongated ports or nozzles 27 and 28 respectively. It will be noted that, as illustrated, the nozzles of each header are spaced apart leaving laterally extending U-shaped recesses or channels c between adjacent outlet ports of the headers, adapted to lead air around the ends of the headers to the inlets 75

of chamber portions B and C. Heated air delivered into channel P through the headers 14 and 15, after being brought into contact with the flights of material within channel P will pass laterally in channels c and, a portion of it will be exhausted through exhaust port 13 which is always at least partially open, and a portion will be diverted into chamber portions B and C respectively when dampers 25 and 26 respectively are open, and redelivered into channel P and into contact with a length of material therein. Thus by regulation of dampers 25 and 26 a portion of the air which has been brought into contact with the material may be by-passed and recirculated through either or both chamber portions B and C.

The dampers 25 and 26 may conveniently be provided with handles, such as 25a illustrated in Figure 1, projecting beyond the side wall of the chamber for facilitating the manual operation of said damper means, and similar means may conveniently be provided for chamber exhaust damper 29 and the dampers 31 positioned within header 14.

As stated above the chamber exhaust port 13 is always partially open, to exhaust moisture bearing air while the length of material is in motion, or to exhaust heated air when the material stops for any reason, and accordingly it is provided with a damper 29 which is preferably of a size to permit some flow through the exhaust port even when it is in closed position. It will be readily seen that by closing dampers 25 or 26 the supply of air to headers 14 or 15 may be cut off, and that by closing both dampers 25 and 26, and fully opening damper 29, the supply of air to the heaters and the fans may be entirely cut off thus cutting out the flow of heated air into channel P, whereupon the heated air will be speedily exhausted from chamber portion A, 40 and particularly from channel P, and will be replaced by room air flowing upwardly into the chamber through bottom opening 12. Thus a protective flow of air at room temperature may be passed through channel P and the interior of the chamber may be speedily cooled at any time when needed to protect material present in the chamber from over drying as, for example, when for any reason the travel of the material is stopped. Our device thus overcomes the disadvantage found in the operation of certain prior art dryers or slashers, particularly those heated by radiant heat, which can be cooled only very slowly and thus are liable to damage the material being dried by over exposing it to a temperature above the critical temperature for the material when the period of contact between the material and the air within the chamber is prolonged as it is for example when the travel of the cloth is stopped or the material is slowed down. For many textile materials for example, a heat of approximately 160° F. is critical if the exposure is prolonged.

Because of the flexibility of our device and the speed with which its internal temperature may be modified, or reduced below the critical temperature for the material being dried, we are able to employ drying temperatures well above those which have heretofore been used for drying textile materials, including lengths of warp and the like. Thus we are able to bring into contact with the length of material within channel P air heated in the range of from 200° F. to 600° F., or even higher, thereby making it possible to speed up the rate of travel of the material during the drying step, and making possible a

corresponding speeding up in the successive steps of fabricating the cloth.

In addition to protecting the material from over-heating by speedily removing heated air from contact with the material being dried, we provide means by which the drying operation may be continued without danger of damaging the material even when the material is advanced very slowly.

It is sometimes necessary to slow down travel of the material being dried without entirely stopping it. Specifically, in the treatment of warp in drying it after the sizing step it is undesirable to entirely stop the travel of the warp since the individual warp threads are in a sticky condition and tend to adhere together or to anything they touch, and if stopped would leave a deposit upon roller 16 which hardens and forms an encrustation likely to cause breakage of the warp threads. When individual warp strands become broken it is accordingly the practice to reduce the speed of travel of the warp without altogether stopping it, and this reduced speed is referred to as the "crawl," and to continue advancing the warp at the "crawl" while the ends of a broken thread are being tied.

For operation at reduced speeds a vertically extending partition 30 is provided within header 14, having between its top and the top of the header the dampers 31 which when closed serve together with partition 30 to close off a portion of the header leaving only section L in communication with the fan means of chamber portion B. As illustrated herein the fan means F are actuated and controlled by motors M through the chain gears g and shafts s respectively. The motors M are preferably two speed motors so that when the travel of the material, in this case specifically a length of warp, is slowed to the "crawl" the motors may be regulated to actuate the fan F of chamber portion B at half-speed, and by closing dampers 31 in header 14 the air supplied by said fan means will be entirely diverted through section L of header 14. Thus only a limited quantity of heated air will be brought into contact with the material passing through channel P, and in only a limited area of the channel, thus preventing overdrying of the material during its movement at the "crawl" speed. To provide further control and prevent air supplied from section L from coming into contact with the warp on its second or downward flight a partition member 12a may be provided opposite section L, extending upwardly from the chamber bottom opening 12, between the upward and downward flights of the warp.

It should be noted that the material to be dried, in passing into and out of chamber 11, contacts only a single support means, roller 16, and that 66% or more of the moisture content of the warp will be removed from the warp prior to contacting the roller, the rate of reduction of moisture content of the warp being substantially greater during its upward flight, when its moisture content is greatest, than during its downward flight.

It will thus be seen that there has been provided by this invention a method and apparatus in which the various objects hereinabove set forth together with many thoroughly practical advantages are successfully achieved. As various possible embodiments might be made of the mechanical features of the above invention and as the art herein described might be varied in various parts, all without departing from the

scope of the invention, it is to be understood that all matter hereinbefore set forth or shown in the accompanying drawing is to be interpreted as illustrative and not in a limiting sense.

What I claim is:

1. Apparatus of the kind described which comprises a chamber communicating at the top with an exhaust flue and having a bottom port to admit a length of material to be dried, air distributing headers extending from opposite sides of said bottom port upwardly through said chamber in the general direction of said exhaust flue each comprising a number of transversely extending elongated air ports spaced apart and thus forming laterally extending air chambers, the ports of each header opening toward the other header, means for supporting a length of material for travel through the channel defined by said headers, partition members within said chamber dividing the chamber into a central portion containing said headers and opposite side portions communicating with the central portion above the upper ends of said headers respectively, means for admitting air into said central portion exteriorly of said channel, means for controlling the volume of air admitted to said side portions respectively from said central portion, air heating means in said side portions respectively, and means in said side portions respectively for forcibly supplying air from said side portions into said headers respectively and through the ports of said headers into the vertically extending channel defined by said headers.

2. Apparatus of the kind described which comprises a chamber communicating at the top with an exhaust flue and having a bottom port to admit a length of material to be dried, air distributing headers extending from opposite sides of said bottom port upwardly through said chamber in the general direction of said exhaust flue each comprising a number of transversely extending elongated air ports, the ports of each header opening toward the other header, means for supporting a length of material for travel through the channel defined by said headers, vertical partition members within said chamber dividing it into a central portion containing said headers and opposite side portions communicating with the central portion above the upper ends of said headers respectively, a horizontally extending partition member extending across said central portion around said headers which are thus disposed partly above and partly below said partition, means for admitting air into said central portion below said partition, means for controlling the volume of air admitted to said side portions respectively from said central portion, air heating means positioned in said side portions respectively, means for forcibly supplying heated air from said side portions into said headers respectively, means for controlling the volume of air supplied to said headers, and means for varying the number of nozzles through which air is discharged from said headers into said channel.

3. Apparatus of the kind described which comprises a chamber having an entrance port to admit a length of material to be dried, an exhaust port, air distributing headers extending from opposite sides of said entrance port in the general direction of said exhaust port, each of said headers comprising a number of transversely extending elongated air ports spaced apart and thus forming laterally extending air chambers, the ports of each header opening toward the other header, means for supporting a length of mate-

rial for travel through the channel defined by said headers, partition members within said chamber dividing the chamber into a central portion containing said headers and opposite side portions communicating with the central portion beyond the ends of said headers respectively, means for admitting air into said central portion exteriorly of said channel, means for controlling the volume of air admitted to said side portions respectively from said central portion, air heating means in said side portions respectively, and means in said side portions respectively for forcibly supplying air from said side portions into said headers respectively and through the ports of said headers into the said channel defined by said headers.

4. Apparatus of the kind described which comprises a chamber having an entrance port to admit a length of material to be dried, an exhaust port, air distributing headers extending from opposite sides of said entrance port in the general direction of said exhaust port, each of said headers comprising a number of air ports, the ports of each header opening toward the other header, means for supporting a length of material for travel through the channel defined by said headers, partition members within said chamber dividing the chamber into a central portion containing said headers and opposite side portions communicating with the central portion beyond the ends of said headers respectively, means for admitting air into said central portion exteriorly of said channel, means for controlling the volume of air admitted to said side portions respectively from said central portion, air heating means in said side portions respectively, and means in said side portions respectively for forcibly supplying air from said side portions into said headers respectively and through the ports of said headers into the said channel defined by said headers.

5. Apparatus of the kind described which comprises a chamber having an entrance port to admit a length of material to be dried, an exhaust port, air distributing headers extending from opposite sides of said entrance port in the general direction of said exhaust port, each of said headers comprising a number of air ports, the ports of each header opening toward the other header,

means for supporting a length of material for travel through the channel defined by said headers, partition members within said chamber dividing the chamber into a central portion containing said headers and opposite side portions communicating with the central portion beyond the ends of said headers respectively, means for admitting air into said central portion exteriorly of said channel, means for controlling the volume of air admitted to said side portions respectively from said central portion, air heating means in said side portions respectively, and means in said side portions respectively for forcibly supplying air from said side portions into said headers respectively and through the ports of said headers into the said channel defined by said headers and means for creating a flow of air through said exhaust port to speedily draw outside air into said chamber to replace the heated air therein whenever the operation of the device is stopped.
